TOOL CHEST

Jacob Bentz, Bismarck, N. Dak.

Application May 2, 1935, Serial No. 19,533

1 Claim. (Cl. 206—16)

The invention relates to a sheet metal carrying case and more particularly to a chest for containing trays for tools or the like.

The primary object of the invention is the provision of a chest of this character, wherein its body is in the form of swinging closure sections, these carrying trays and through linkage the trays are shifted from a stacked superposed relation to each other when the cover sections are closed to a position for convenient access thereto on the opening of the cover sections, the cover sections being opened and closed through linkage with a handle there being no liability of the chest becoming accidentally opened when carried in the hand of a person.

Another object of the invention is the provision of a chest of this character, wherein the handle for the carriage of the chest operates upon the cover sections thereof and these carry the trays, the latter and the handle being connected through linkage with said sections for convenience in the handling of the tray for the opening of the same and having access to the interior thereof, the chest in its entirety being of novel construction.

A further object of the invention is the provision of a chest of this character, which is simple in construction, thoroughly reliable and efficient in its operation, compact, strong, durable, susceptible of a variety of uses, readily portable and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claim hereunto appended.

In the accompanying drawings:

Figure 1 is a perspective view of the chest constructed in accordance with the invention.

Figure 2 is a top plan view with the cover sections open.

Figure 3 is a vertical transverse sectional view showing by full lines the cover sections open and by dotted lines one of the cover sections closed.

Figure 4 is a sectional view on the line 4—4 of Figure 3 looking in the direction of the arrows.

Similar reference characters indicate corresponding parts throughout the several views in the drawings.

Referring to the drawings in detail, the chest is of a neat and compact kind made from sheet metal and has a pair of cover sections 5 swingingly connected to a box-like body section 6,

the pivots for the cover sections being indicated at 7 and are engaged in the sides 8 of said cover sections and the box-like body section 6. These cover sections 5 meet and separate at a vertical center of the chest. Within the cover sections 5 are trays 9 and 10, respectively, which are movable with said cover sections and through linkage 11 will be brought into a vertical stack superposed with relation to each other when the cover sections 5 are closed and on the opening of the latter 10 these trays 9 and 10 swing laterally so that the trays 10 will be stepped to one side of the trays 9 and yet maintained in a true horizontal position for free access thereto.

The linkage for the trays 9 and 10 in each cover section 8 includes the links 12, 13 and 14, respectively, the latter being pivoted to the cover section 5 and the tray 10 while the link 13 is pivoted to said tray 10, tray 9 and the body section 6 while the link 12 is pivoted to the tray 20 9 and the body section 6 and such links 12, 13 and 14 are disposed in parallel relation to each other and spaced one from the other.

One or more of the trays may have a transverse partition 15 for dividing it into compartments handy for reception of articles.

One cover section carries a latch or lock 16 while the other section carries a hasp or keeper 17 for engagement with the lock 16 when the cover sections are closed.

Pivoted to the cover sections at opposite sides 8 thereof are pairs of links 18, these being pivoted at 19 to a handle bar 20 bridging the chest, the pivots for the connection of the links 18 for the cover sections being indicated at 21. Thus it will be apparent that a toggle action is had between the cover sections by the links 18 so that when the cover sections are swung to open position the trays will be automatically shifted therewith in a manner as previously described. On pulling upwardly on the handle bar 20 when the cover sections 5 are open these will be swung to closed position and it is impossible for the accidental opening of the cover sections when the chest is suspended from the handle 20 on the carrying of said chest in the hand of the user. The top or outer flanges of the cover sections 5 are preferably formed with inwardly extending portions whose ends are formed with ribs or flanges 50, that are contacted by the upper or outer trays 15 50 to hold the series of trays in horizontal position when the cover sections are opened and which likewise limit the swinging of said cover sections to said open position. The links hold the trays in horizontal position when the cover sections are 55

moved to closed position, when of course, the chest is in vertically supported position.

What is claimed is:

5 A tool chest comprising in combination a box-like body having flanged closures pivoted to the ends thereof and having handle connected links pivoted to the closures for swinging the same to open or closed position with respect to the body and trays pivoted between the side flanges of the

closures and having a linkage between each other and the body to cause such trays to swing to a plane parallel with that of the body when the closures are moved to open or to closed position, and ribs formed on the closures to contact with 5 certain of said trays to hold all of the trays in parallel position and to limit the movement of the closures when in open position.

JACOB BENTZ.
